[57] CLAIM

The ornamental design for occludator, substantially as described and shown.

DESCRIPTION

FIG. 1 is a top plan view of the inventive occludator;
FIG. 2 is a bottom plan view of the occludator;
FIG. 3 is a front view of the occludator;
FIG. 4 is a right side view of the occludator;
FIG. 5 is a rear view of the occludator;
FIG. 6 is a sectioned view of the occludator taken along the line 6—6 of FIG. 3;
FIG. 7 is a perspective view of the occludator;
FIG. 8 is a perspective view of the occludator showing an opened upper element;
FIG. 9 is a perspective view of the occludator showing a middle element laid flat; and
FIG. 10 is a perspective view of the occludator showing upper, middle and lower elements laid flat.
The left side of the occludator which is not shown is a mirror image to the right side which is shown in FIG. 4.

FIG. 1**FIG. 2****FIG. 3****FIG. 4****FIG. 5****FIG. 6****FIG. 7****FIG. 8****FIG. 9**

FIG. 10
